UNITED STATES PATENT OFFICE.

ROBERT von STEIGER, OF ROSENBERG, SWITZERLAND, ASSIGNOR TO THE FIRM OF
GEBRUDER BÜHLER, OF UZWIL, SWITZERLAND.

DISCHARGING DEVICE FOR KILN FURNACES.

Specification of Letters Patent. Patented Apr. 11, 1922.

1,412,811.

Application filed August 22, 1919. Serial No. 319,127.

To all whom it may concern:

Be it known that I, ROBERT von STEIGER, a citizen of the Republic of Switzerland, residing at Rosenberg, Niederuzwil, Switzerland, have invented certain new and useful Improvements in Discharging Devices for Kiln Furnaces; and I do hereby declare the following to be a clear, full, and exact description of the invention, such as will enable others skilled in the art to which it appertains to make and use the same, reference being had to the accompanying drawing, and to letters or figures of reference marked thereon, which form a part of this specification.

This invention relates to improvements in discharging devices for kiln-furnaces for burning sintering material, such as cement, magnesite and the like.

The object of this invention is to provide a discharging device of the kind referred to comprising one or several breaking beams adapted to be moved in their longitudinal direction on a stationary furnace-bed by a driving mechanism, so that the burnt material is loosened, broken up and discharged by said beams.

This invention will now be more particularly described with reference to the accompanying drawing illustrating by way of example two modes of carrying out the invention. In this drawing:

Fig. 1 is a vertical section on the line I—I of Fig. 3 through the lower portion of the kiln-furnace,

Fig. 2 is a vertical section on the line II—II of Fig. 3 and Fig. 3 is a plan view of this furnace.

Fig. 4 is a vertical section corresponding to Fig. 2 through a modified construction of the furnace-bed.

Fig. 5 is a perspective view of portions of two breaking beams, and

Fig. 6 is a vertical cross-section through a modification of a detail.

Referring to the drawing, 1 designates the kiln, 2 the lining, 3 an intermediate shaft wall, 4 the external wall of the kiln-furnace, 5 the furnace-bed and 6 the breaking beams. Each of the latter is connected at 7 to a crank mechanism 8 adapted to impart to the corresponding breaking beam 6 a to and fro movement in its longitudinal direction. The embodiment shown comprises two such beams 6; when required,

also only one or more than two such beams may be provided. Preferably, the two breaking beams 6 are moved simultaneously in the same direction; by providing crank arms 8 at 180° they can be moved, however, 60 also in opposite directions. The different beams 6 can have the same or different strokes, and the stroke of each beam may be varied by adjusting for instance the point at which the crank pin is fixed to the 65 crank arm 8 within the slot 9. The beams 6 have preferably a pentagon-like cross-section, one of the corners extending upwards. These beams 6 are provided with breaking teeth.

The operation of a device as hereinbefore described is for instance as follows:

When a to and fro movement is imparted to the two beams 6, the lowermost portion of the column of material contained in the 75 kiln and consisting mostly of large pieces or frequently also of a single block constituted of material that has sintered together, is acted upon by the teeth and corners of said beams 6, milling off the material, breaking it up and loosening it, whereby the teeth of these beams 6 press part of the material against the lower edges of the kiln. Thus, the material in the kiln 80 is reduced into small pieces and the broken 85 pieces are discharged at the front and rear end of the furnace.

For the purpose of increasing the discharging action, it is found sometimes advisable to provide scooping bars 10 (Fig. 5) 90 arranged transversely of the beams 6 and adapted to push the broken up material forwards and to sweep the whole width of the cross-section of the kiln. The scooping bars 10 can be designed either as smooth beams 95 as shown in Fig. 5, or they may be provided on their outer surface with teeth or projections 11 (see Fig. 6) in order to further break up the material against which they are forced. As illustrated, the scooping bars 10 are preferably secured to the breaking beams 6 so that they are moved together with the latter which preferably have all the same stroke and are all moved in the same direction.

As shown, the upper surface of the furnace-bed 5 is preferably horizontal over its whole length. Should it be designed slightly inclined towards the discharge-ends, the slope of this inclined surface must be so 110

small that the material resting thereon is prevented from starting of itself to slide down said surface. The upper surface of the furnace-bed 5 projects at both discharge sides of the kiln at least to an amount beyond the cross-section of the kiln determined by the angle of repose of the material. Thus, any irregular discharge of fine material, which would detrimentally influence 10 the regular working of the furnace, is prevented. In the embodiment of the invention illustrated in Figs. 1 to 3, the bottom of the kiln is designed as a massive body; but as shown in Fig. 4, it can be designed 15 also as a grate in order to allow an admission of combustion air from beneath. In such a case it is advisable to make the apertures between the single grate bars not larger than 10-15 cm., in order to prevent 20 too great a discharge of fine material through said apertures.

What I claim now as my invention is:

1. In a sintering furnace, a discharge device comprising at least one longitudinally reciprocable breaking bar reciprocable on the charge supporting surface.
2. In a sintering furnace, a discharge device comprising at least one bar longitudinally reciprocable on the charge supporting 30 surface, said bar being substantially wedge shaped in section and breaker teeth on the surface of said bar.
3. In a sintering furnace, a discharge device, a longitudinally reciprocable breaker bar having laterally projecting scooping bars.
4. In a sintering furnace, a discharge device, a longitudinally reciprocable breaker

bar having laterally projecting scooping bars and breaker teeth on the latter bars. 40

5. A discharge device for sintering furnaces comprising at least one longitudinally reciprocable hollow bar whose upper surface is inclined, and having laterally projecting scooping bars, and breaker teeth on 45 said bars.

6. A discharge device for sintering furnaces comprising a plurality of breaker bars having breaking teeth on the active surfaces thereof and separate means for longitudinally reciprocating said bars in unison and a charge support on which said bars recipro- 50 cate.

7. In a sintering furnace a shaft, a charge supporting surface spaced below said shaft 55 and whose extent beyond the inner walls of the shaft is dependent upon the angle of repose of the material being sintered, at least one longitudinally reciprocable bar on said surface beneath the charge, and breaker 60 teeth on said bar.

8. In a sintering furnace, supporting means for the charge, at least one breaking bar reciprocable on said means and operating to discharge material at both ends of 65 said bar.

9. In a sintering furnace, supporting means for the charge spaced from the bottom of the furnace shaft, a breaking bar and means to reciprocate said bar on the charge 70 support to discharge the furnace product at opposite ends of said supporting means and bar.

In testimony that I claim the foregoing as my invention, I have signed my name.

ROBERT VON STEIGER.
